UNITED STATES PATENT OFFICE.

WILLIAM IRING, OF NEW YORK, N. Y.

WRENCH.

1,053,181.

Specification of Letters Patent.

Patented Feb. 18, 1913.

Application filed June 18, 1912. Serial No. 704,370.

To all whom it may concern:

Be it known that I, WILLIAM IRING, a citizen of the United States, residing in the city, county, and State of New York, have 5 invented certain new and useful Improvements in Wrenches, of which the following is a specification.

My invention relates to wrenches and is an improvement upon the wrench comprised 10 in the patent to Adalbert Iring, No. 1,028,883, dated June 11, 1912, the object being to provide improved means for securing the movable jaw in adjusted position, as will more fully appear in the following 15 description and claim.

Referring to the accompanying drawing:—Figure 1 is a side elevation of the wrench shown partly in section with the adjustable jaw locked. Fig. 2 is a similar 20 view as Fig. 1 with the adjustable jaw unlocked and the handle broken away, and Fig. 3 is a view of Fig. 1 viewed from the right with the handle broken away.

The wrench comprises a handle *a* having 25 a head *b* fixedly secured or integrally formed thereon. The head is formed with a jaw *c* preferably positioned at the rear end thereof, and has a longitudinal chamber *d* passing through it. The wrench is provided 30 with a flat surface *e* having a longitudinal slot *f* communicating with the chamber below it. A movable jaw *g* is disposed to slide upon the surface *e* and is provided with a tongue *h* which engages with the chamber 35 *d* to secure the jaw firmly in sliding relation on the surface *e* of the wrench. The union of the wrench and jaw may be made in several ways, the preferred type being made as shown, by forming the chamber *d* rounding 40 at the top, and forming the tongue with rounding longitudinal flanges on either side to engage the rounding parts of the chamber. This makes a strong joint and one that is simple to construct, but any form of joint 45 of usual construction will answer the purposes of my invention.

The bottom of the tongue *h* is formed with teeth *i* for locking the jaw in adjusted position with the teeth *j* formed on a locking 50 bar *k* disposed within the chamber *d*. The bar is secured to the chamber through means of the pin *l* and slots *m*, the pin preferably passing through the bar and the slots preferably being formed through the head of 55 the wrench, although the reverse may be followed if desired.

The bar *k* is held normally up against the movable jaw *g* by means of a spring *n* secured to one end of the bar as by the screw *o*, and curved or bent to set upon the base 60 of the chamber at its middle portion, and to contact with the bar at its opposite end. The spring is in this position, under tension to enable it to hold the bar firmly against the jaw. By this construction the bar and 65 jaw are always locked together, as shown in Fig. 1, unless the bar is manually operated to disengage them. This is accomplished by forcing the forward end of the bar downward as shown in Fig. 2, the bar being ex- 70 tended beyond the chamber to form the handle *p* to manipulate its movement downward. When the bar is thus moved downward the jaw *g* is free to be slid in either direction to adjust it relative to the fixed jaw *c* to accommodate the nut (not shown) on which the wrench is to be used. When the bar is released it springs into engagement with the 75 jaw and firmly holds it ready for use. Where the jaw is open wider than is necessary, it may be moved to proper position without manually depressing the bar, on account of the preferred form given the teeth. 80

It is desirable that the chamber *d*, the bar *k*, the pin *l* and the slots *m* be given suitable 85 relative sizes so that the bar may be turned transversely within the chamber to free the pin from its engaging slots in order that the bar may be easily placed in position or removed when desired. The bar is extended 90 beyond the chamber at its rear end to form another handle *q* to aid in turning it as above described, and also for holding the bar down at that end if so desired, when releasing the adjustable jaw. When the bar 95 is pressed down at its forward end, it rises at its rear end until the pin *k* strikes the ends of the slots *m*. It is therefore obvious that if the end *q* is depressed with the end *p*, the bar will not have to be forced down as 100 far as when only the end *p* is depressed. The chamber *d* is however made deep enough to provide for either operation. This improved construction of the locking 105 bar enables the teeth thereon and the teeth of the movable jaw to be normally in uniform engagement, that is to say, it distributes the force, applied at the handle in operating the wrench, among all the teeth on the jaw, instead of only upon a few as in 110 the case where the bar is pivoted in the manner shown in the patent above referred to.

The proper locking of the bar and jaw will also continue regardless of the wear of the parts. Such a construction also provides for an easy removal and replacement of the locking bar from the wrench, no tool being necessary to accomplish this.

Having thus described my invention, I claim:

A wrench comprising a hand lever having
10 a head at one end; a jaw at one end of the head; a chamber through the head, a rack bar within the chamber, a pin extending through the bar and having its ends disposed in slots formed in the head, a spring
15 for holding the bar in raised position at

both ends, an operating handle formed by projecting the forward end of the bar without the chamber, a movable jaw having a rack for engagement with the rack of the bar when in normal position to lock said jaw against outward displacement from the fixed jaw, and means for securing the jaw in sliding relation in the head.

This specification signed and witnessed
this 17th day of June A. D., 1912.

WILLIAM IRING.
